UNITED STATES PATENT OFFICE.

WILLIAM McCONWAY, JR., OF PITTSBURGH, PENNSYLVANIA, ASSIGNOR TO THE
McCONWAY & TORLEY COMPANY, OF PITTSBURGH, PENNSYLVANIA, A CORPORA-
TION OF PENNSYLVANIA.

DRAFT APPLIANCE FOR RAILWAY-CARS.

1,021,419.

Specification of Letters Patent. Patented Mar. 26, 1912.

Application filed October 31, 1911. Serial No. 657,819.

To all whom it may concern:

Be it known that I, WILLIAM McConway, Jr., a citizen of the United States, residing at Pittsburgh, in the county of Allegheny and State of Pennsylvania, have invented certain new and useful Improvements in Draft Appliances for Railway-Cars; and I do hereby declare the following to be a full, clear, and exact description of the invention, such as will enable others skilled in the art to which it appertains to make and use the same.

My invention relates to the construction of draft appliances for railway cars and is especially directed to the production of simple, compact and efficient devices for supporting the coupler so as to permit it to readily yield vertically when the car to which it is attached passes over vertical curves in the track.

Generally stated, the principal feature of the invention consists in slidably mounting upon a vertically movable coupler a follower which is movable vertically with respect to said coupler, a spring which is carried by the coupler being interposed between the follower and coupler, and the follower being supported by a yoke or carry iron through which the coupler extends and with respect to which the coupler is capable of vertical movement.

In the drawings illustrating my invention, the scope whereof is pointed out in the claims, Figure 1 is a plan view of a draft appliance embodying my invention; Fig. 2 is a view, partly in side elevation and partly in vertical central section, illustrating the devices shown in Fig. 1; Fig. 3 is a detail view, partly in plan and partly in horizontal central section, showing the coupler and the devices by which it is yieldingly supported at its outer end; Fig. 4 is a detail vertical section taken in the plane of the line 4—4, Fig. 3; and Fig. 5 is a detail vertical section taken in the plane of the line 5—5, Fig. 4.

Like symbols refer to like parts wherever they occur.

I will now proceed to describe my invention more fully, so that others skilled in the art to which it appertains may apply the same.

As my invention is especially applicable to draft appliances which are used on in-

terurban cars, where horizontal and vertical curves in the track are sharp and generally numerous, I have illustrated it as applied to a coupler which is pivotally connected to the car so as to be capable of swinging laterally in both directions from a central position.

In the form of construction illustrated in the drawings, the coupler 1 is yieldingly and pivotally connected to the car through the intervention of a draft rigging comprising a casing or housing 2 which is open at its outer end and which is provided with a detachable bottom 3 which permits the insertion of a draft spring 4 and followers 5, the draft spring being interposed between the followers, and a yoke 6, which is attached to the coupler, passing around said followers in the usual well known manner. The rear end of the draft gear casing 2 is provided with an aperture that receives a bolt 7 which pivotally connects the casing 2 to a supporting bracket 8 which is rigidly attached to the car frame.

As a convenient means for connecting the coupler to the car so as to permit it to move vertically, the rear end of said coupler may be pivotally connected to the draft yoke 6 by means of a horizontally extending pivot bolt 9, the inner end of the coupler being preferably formed with rounded edges, as at 10, 10, which, when the coupler moves either upwardly or downwardly from its normal position, as indicated in dotted lines in Fig. 2, operate as cams to force the adjacent forward follower 5 rearwardly a short distance, the compression of the draft spring 4 being thus utilized in normally maintaining the coupler at the proper height above the rails.

The forward end of the coupler 1 is supported from the car by a yoke or carry iron 11 which, if the coupler be pivotally movable laterally as in the present instance, may be advantageously arranged to slide upon the flanges 12 of a curved supporting rail 100 having plates or brackets 13 and 14 by which it may be bolted to the under side of the car, the carry iron 11 being provided at its upper end with inwardly projecting flanges 11^a forming a slot of T cross section which receives the correspondingly shaped supporting rail from which the carry iron depends. For convenience of assembly the

carry iron 11 may have a detachable bottom 11^b which is secured to the body of the carry iron by means of bolts 15.

Seated upon the bottom 11^b of the carry iron 11 is a follower 16 having arms 16^a which extend upwardly on opposite sides of the coupler 1, the coupler, as more particularly shown in Figs. 3 and 4 being provided upon each side with vertically extending ribs 1^a forming guideways which receive the arms 16^a of the follower.

Upon its interior the coupler 1 is formed with a spring-seat 1^b which is arranged in alignment with an aperture 1^c in the coupler 15 through which a spring 17 projects, the upper end of said spring being seated upon the spring seat 1^b and its lower end resting upon a corresponding spring-seat 16^b formed on the upper face of the follower 16. The 20 extent of upward movement of the coupler with respect to the follower is preferably limited by means of a vertically extending bolt 18 which loosely passes through both the coupler 1 and follower 16, as shown in 25 Figs. 4 and 5.

When a car equipped with draft appliances embodying my invention passes over vertical curves in the track the coupler moves upwardly or downwardly as the case 30 may require. In moving downwardly from its normal position the coupler slides vertically with respect to the follower 16, thus energizing the spring 17 so that it may subsequently return the coupler to normal position. In moving upwardly from its normal position, as the height of the opening in the yoke or carry iron 11 permits it to do, the coupler 1, acting through the bolt 18, lifts the follower 16 from its seat upon the 40 carry-iron 11, the weight of the parts being sufficient to cause their return to normal position.

As heretofore described, it is preferred to 45 so form the rear end of the coupler and to so connect it to the draft gear that a vertical movement of the coupler 1 in either direction from its normal position causes the draft spring 4 to be slightly compressed, since the draft spring 4 is thus utilized, not

only to yieldingly maintain the coupler in 50 a vertically centralized position, but also to assist the supporting spring 17 in raising the coupler after it has been depressed and to assist the force of gravity in restoring the coupler to normal position after it has been 55 elevated.

As the follower 16 moves with the coupler during any longitudinal movement of draft and buffing, the bottom plate 11^b of the supporting yoke or carry-iron 11 should be 60 made wide enough to extend under the follower 16 when the coupler is in any position it may assume in service.

I claim:

1. In a draft appliance for railway cars, 65 the combination with a vertically movable coupler having a spring seat upon its interior and guideways upon its exterior, of a follower having upwardly extending portions which are slidably in the corresponding 70 guideways upon the exterior of the coupler, and a spring resting upon said follower and upon the said spring seat of the coupler.

2. In a draft appliance for railway cars, 75 the combination with a vertically movable coupler having a spring seat upon its interior and a spring receiving aperture in alignment therewith, a follower having upwardly extending portions which slidably engage the coupler, said follower and coupler being relatively movable vertically, a spring extending through the said aperture in the coupler and bearing upon said spring seat and follower, means for limiting the extent of upward movement of the coupler 85 with respect to the follower, and means carried by the car for supporting said follower, said follower supporting means having an opening through which the coupler passes and within which the coupler is movable 90 vertically.

In testimony whereof I affix my signature, in the presence of two subscribing witnesses.

WILLIAM McCONWAY, JR.
